UNITED STATES PATENT OFFICE

ARTEMUS R. RICHTMYER, OF NEW YORK, N. Y.

DESIGN FOR A TEXTILE FABRIC

Application filed April 20, 1932. Serial No. 43,550. Term of patent 14 years.

To all whom it may concern:

Be it known that I, ARTEMUS R. RICHTMYER, a citizen of the United States and a resident of New York, borough of Manhattan, in the county of New York and State of New York, have invented the new, original, and ornamental Design for a Textile Fabric, of which the following is a specification.

Reference is had to the accompanying drawing forming part thereof, wherein—

The figure of the drawing is a plan view

of a piece of textile fabric showing my design, the portion enclosed within the dot and dash lines being the repeatable design in it, the same being repeated in the relation indicated by the extensions beyond the unit boundaries.

I claim:

The ornamental design for a textile fabric substantially as shown and described.

ARTEMUS R. RICHTMYER.
